UNITED STATES PATENT OFFICE

WILLIAM J. KELLY, OF BROOKLYN, NEW YORK, ASSIGNOR OF ONE-HALF TO ARTHUR D. BASCH, OF BROOKLYN, NEW YORK

METHOD OF MAKING SHOES

Original application filed March 19, 1926, Serial No. 95,853. Divided and this application filed August 12, 1929. Serial No. 385,390.

My invention relates to the art of making shoes, and the principal object thereof is a new and improved method of making shoes as hereinafter set forth in the specification and claims, reference being had to the accompanying drawings in which—

Figure 1 is a side elevation of a shoe in process of manufacture with the upper tacked on the last.

10 Figure 2 is a vertical cross section through line 2—2 of Figure 1 showing the first step of the method.

Figure 3 is a similar view after the insole has been attached in position.

15 Figure 4 is a detailed cross sectional view indicating one step in the production of a shoe according to this method.

Figure 5 is a view similar to Figures 2 and 3 showing the shoe after the completion of 20 the sewing step illustrated in Figure 4.

Figure 6 is a view similar to 5 showing the out sole applied.

This application is a division and continuation of my copending application Serial No. 25 95,853, filed March 19, 1926.

In the drawings, the numeral 1 designates the last and 2 an upper, and in the first step of this method the upper 2 is drawn over the last in any manner as, for instance, by a pull- 30 over machine and the marginal portions are drawn down practically in the edges or corners of the last and fastened by lasting tacks 3. It is to be expressly understood that these tacks are driven into the sides of the last ad- 35 jacent the bottom edges thereof, and not into the bottom of the last in accordance with the usual practice.

The next step is illustrated in Figure 3 and includes the application of the insole 4 40 which may be held in place by any suitable means, such as the tacks 5. The free edges of the upper are turned outwardly and overlap and rest upon the protruding margins or edges of the insole 4, as clearly illustrated in 45 Figure 3. It is to be noted in Figure 3 that the tacks are bent upwardly and are at an acute angle to the extended edges of the upper and insole.

The next step involves placing this lasted 50 upper upon a tiltable table A with the insole

4 in contact with the table. The table and last are tilted or shifted to an inclined position, as indicated in Figure 4, to present the corner portion of the lasted upper to the shoe or roller C of the presser foot of the sewing machine. The lasted upper is thus supported upon the table and is moved or advanced by the workman so as to present the upper to the stitching mechanism E.

After the tacks have been driven into the 60 last and the pulling device released, the upper becomes somewhat loosened. In the sewing operation the upper is forced downwardly and against the last by the roller or presser foot C and this results in tightening 65 the upper on the last and especially around the bottom edges or corners of the last so that a snug fit is obtained. At the same time that the presser foot is performing its functions, the tacks of the upper are forced down and the upper is stitched to the sole so that the seam passes over the tacks and hides or covers the tack holes.

The roller C engages the upper at the angle formed by the out turned margin, and pressing thereagainst acts to crowd or force that portion of the upper somewhat below the last so that the stitches 6 pass through the upper and insole at an angle and as close as possible to the corner or angle 7 of the upper. The roller tucks the upper practically below the edge of the last, this operation being facilitated by utilizing the inclined table, the inclination of which may be varied as necessary.

This mechanism and the details of the operation thereof are all disclosed and described in full in my above-mentioned copending application.

When the sewing operation of Figure 4 is completed, the lasted upper has the appearance shown in Figure 5. Then the outsole 8 is sewed thereto by means of stitches 9, see Figure 6.

In my copending application for method of making shoes, Serial No. 549,515, filed July 8, 1931, I have disclosed and claimed a method of pulling an upper downwardly over a last simultaneously at opposite sides of the 100

last and then driving tacks into the sides of the last near the bottom edges thereof.

It is therefore seen that by this method it is possible to produce a shoe quickly and economically and that a minimum amount of expenditure of time and labor is used. Furthermore, the shoe produced is correctly lasted and the various parts thereof are permanently secured together to give good wear, pleasing appearance and proper fit.

What I claim is:

1. In the art of making stitchdown shoes, the process which comprises drawing or pulling an upper downwardly around a last at opposite sides thereof and close to the bottom edges thereof and fastening the upper to the last by tacks driven through the upper and into the sides of the last at the forepart and adjacent the edges thereof, the edges of said upper being free and adapted to be bent laterally, imposing an insole upon the drawn upper and securing the insole to the last so that the free edges of the upper rest upon and are supported by the margins of the insole and at a sharp angle to the upper and last, and securing said insole and upper together by means passing through the upper over the line of tacks while at said sharp angle and at an inclination to the vertical.
2. The method of making stitchdown shoes, which comprises drawing or pulling an upper downwardly over a last, temporarily fastening the upper to the last near the bottom edges thereof by tacks driven through the upper and into the sides of the last adjacent the bottom edges thereof and leaving the edge portions of the upper free, mounting a sole on the drawn or pulled upper and bending the tacks upwardly, and then stitching the assembly through the angle of the upper and sole with the seam passing over the line of tacks so that when the tacks are withdrawn, the holes left by the tacks will not be seen.
3. The method of making stitchdown shoes, which comprises, pulling an upper downwardly over the toe and on opposite sides of the last, temporarily fastening the upper to the last near the bottom edges thereof by tacks driven through the upper and into the sides of the last adjacent the bottom edges thereof and leaving the marginal portions of the upper free, mounting a sole on the drawn or pulled upper and stitching the sole to the edge portions of the drawn or pulled upper with the seam passing over the line of the tack holes.

4. The method of making stitchdown shoes, which comprises, drawing or pulling an upper downwardly over a last so that the edges of the upper extend beyond the edges of the last, driving tacks into the sides of the last near the bottom edges thereof and leaving the edge portions of the upper free, mounting a sole on the drawn or pulled upper and securing the sole to the edge portions of the

drawn or pulled upper at an angle on a line with the tacks, the securing operation forcing the tacks and the upper downwardly so that the seam covers the holes left by the tacks when the tacks are afterwards withdrawn.

5. The method of making stitchdown shoes, which comprises, drawing or pulling an upper over a last, temporarily fastening the upper to the last near the bottom edges thereof by tacks driven through the upper and into the sides of the last adjacent the bottom edges thereof and leaving the edge portions of the upper free, mounting a sole on the drawn or pulled upper and bending the tacks upwardly, and then stitching the sole to the edge portions of the drawn or pulled upper at an angle and with the seam passing over the line of the tacks, the stitching operation forcing the bent tacks and upper downwardly so that the line of stitching passes over the tack holes.

6. The method of making stitchdown shoes, which comprises, drawing or pulling an upper downwardly over the toe and at opposite sides of a last, driving tacks through the upper into the toe and sides of the last close to the bottom edges thereof, mounting a sole on the drawn or pulled upper and bending the tacks upwardly, and then stitching the assembly through the angle of the upper and sole while forcing the upper downwardly to tightly engage the last.

7. The method of making stitchdown shoes, which comprises, drawing or pulling an upper over a last, temporarily fastening the upper to the last near the bottom edges thereof by tacks driven through the upper and into the sides of the last adjacent the bottom edges thereof and leaving the edge portions of the upper free, mounting a sole on the drawn or pulled upper, and then stitching the sole to the edge portions of the drawn or pulled upper at an angle and with the seam passing over the line of the tack holes, the stitching being done while the upper is forced downwardly to the bottom edges or corners of the last so that the upper is made to tightly engage the last.

8. The method of making stitchdown shoes, which comprises, drawing or pulling an upper downwardly over a last so that the edges of the upper extend beyond the edges of the last, driving tacks into the sides of the last near the bottom edges thereof and leaving the edge portions of the upper free, mounting a sole on the drawn or pulled upper and stitching the sole to the edge portions of the drawn or pulled upper at an angle on the line with the tacks, the stitching forcing the upper downwardly and around the bottom edges or corners of the last.

9. The method of making stitchdown shoes, which comprises, drawing or pulling an upper over a last, temporarily fastening the upper to the last near the bottom edges thereof

by tacks driven through the upper and into the sides of the last adjacent the bottom edges thereof and leaving the edge portions of the upper free, mounting a sole on the
5 drawn or pulled upper, and then securing the sole to the edge portions of the drawn or pulled upper at an angle and with the seam passing over the line of the tack holes, the securing operation being done while forcing
10 the upper against the side of the last and downwardly to the bottom edges or corners of the last.

In testimony that I claim the foregoing, I have hereunto set my hand this 9th day of
15 August, 1929.

WILLIAM J. KELLY.
